DOMESTIC HEATER

Harry A. Grine, White Plains, N. Y.

Application January 20, 1933. Serial No. 652,612

11 Claims. (Cl. 122—210)

This invention relates to attachments for use in coal burning domestic heaters to adapt them for efficient oil burning or underfeed coal stoker operation.

5 Coal furnaces for domestic heating of either a hot water or steam type are designed for operation with relatively deep fire beds. In normal operation the coal fire in a domestic furnace gives off its heat units continuously at a 10 relatively slow rate and because of the large area of fire which is in contact with the heating surfaces of the furnace, a large portion of the heat is transmitted directly to the surrounding heating surfaces by conduction. The relatively slow 15 flow of air through the firebed even when the drafts are wide open permits the transfer of a considerable amount of heat by convection although the furnace may be provided with relatively short combustion gas travel. The radi- 20 ant heat of a coal fire accounts for only a portion of the total heat evolved, even when the furnace is being forced.

In the past oil burning and underfeed coal 25 stoker equipment has been installed in domestic heaters designed for hand firing with coal. The results have been unsatisfactory in many regards, particularly from the point of view of efficiency. An oil burner, in contradistinction to a coal fire, gives off heat at a very rapid rate 30 and is operated for short periods of time only. Such equipment is normally provided with a blower creating an air blast which atomizes the oil and as a result the combustion gases pass through the furnace at a higher rate of speed 35 so that the transfer of heat from the gases by convection is inefficient. Since the flame in most designs is not in contact with the side heating surfaces of the furnace practically no heat is transferred by direct conduction and in fact a 40 very large proportion of the heat absorbed from the oil flame is in the form of radiant heat which is of course, only a minor part of the total heat evolved in any equipment which pretends to complete combustion of the oil. As a result ex- 45cessive high stack temperatures result and a considerable portion of the heat evolved is wast- ed up the stack.

The low efficiency of oil burning equipment in 50 domestic furnaces designed for burning coal has lead to the construction of special oil burning heaters in which the gas travel is lengthened and the amount of heat absorbing surface is very 55 greatly increased in order to permit absorbing the heat of the oil flame during the intervals when the oil burner is operating. These special

furnaces have also been provided with a larger number of passes more closely spaced than in the case of coal fired equipment, and the high velocity of the gases driven by the air blast of the burner results in sufficient turbulence so that 60 all portions of the gas stream come in contact with the water cooled heat absorbing surfaces and give up their heat by convection.

Special oil burning furnaces are expensive because they require an entire new installation and 65 the coal burning furnaces have to be scrapped. It has been proposed to slightly increase the efficiency of oil burning equipment by placing a disc or other small baffle or deflector over the burner, the baffle usually being constructed of fire brick. 70 This attempt to improve the efficiency of oil burning equipment applied to coal fired domestic furnaces does to some extent, increase the turbulence of the combustion gases and deflecting them to some extent against the side walls of 75 the heater. At the speed with which the gases are driven through the furnace, the amount of heat which is transferred by convection is still too low for efficiency because of the short gas travel and particularly the insufficient heating 80 surface. The most serious lack in a fire brick deflector disc or baffle lies in the fact that it does not add any additional heat absorbing surface and the improvement which it effects consists 85 solely in a somewhat better utilization of a part of the heat absorbing surface already present in the boiler. Even the slight increase in heat absorbing efficiency which is effected by the use of fire brick baffles is at the expense of some loss 90 of radiant heat which is reflected down to the bottom of the ash pit and results in a higher ash pit temperature and therefore greater heat losses through the ash pit walls which are normally not water jacketed.

The present invention provides the required 95 additional heating surface needed to absorb heat at the higher rate at which it is evolved in an oil burner, assures sufficient length of gas travel and turbulence to efficiently absorb the heat of combustion gases and permits a low stack temper- 100ature with the corresponding increase in efficiency in utilizing the heat units of the oil. The objects of the invention are effected without the necessity of any dismantling of the coal burning equipment other than that required for installation of the oil burner, and the added members are simple and cheap in construction and can be installed with a minimum of labor.

Essentially the present invention consists in 110 hollow members which are inserted through the

fire door of the furnace and so disposed as to add an additional pass to the furnace. The problem of installing a satisfactory heating surface through the fire door is a difficult one because 5 the fire door is normally by no means as wide as the corresponding section of the fire box and a small heat absorbing member is but little better than a fire brick deflector because the gases flow rapidly around it without being forced into 10 contact with the water cooled walls of the boiler itself. According to the present invention the auxiliary heating surface is formed in two or more units, each of sufficiently less width than the fire door to be inserted therethrough, but 15 when fitted together substantially extend across the whole of the fire box area so that they constitute a true additional pass to the boiler. The assembled units are of a total width substantially equal to that of the fire box, but are shorter in a 20 fore and aft direction so that the combustion gases from the oil burner flow up over the forward or rear end depending on the location of the opening to the next higher pass.

A further important advantage of the present 25 invention lies in the fact that the additional heating surface coupled with the improved utilization of the heating surface already present in the boiler by reason of the baffling effect, very markedly increase the capacity of the boiler. 30 Not only does this permit efficient operation of an oil burner but it remedies the difficulty of inadequate boiler size which is frequently encountered in houses which have been built to sell and in which the heating system has been 35 skimped by using a boiler of inadequate capacity. To such installations, the present invention not only presents the advantages of efficient oil burner operation but it so increases the capacity of the boiler that the inadequacy of the system 40 is remedied.

It is necessary to assure a satisfactory rapid circulation of water through the auxiliary heating surfaces particularly since its heat absorption 45 is relatively high, in fact, higher than any other portion of the heat absorbing surface of the furnace because it is located immediately above the flame of the burner and hence, absorbs the full radiant heat. At the same time water must enter and leave through the fire door opening or through the small holes which are normally provided in the water jacket for the insertion of heating coils of domestic hot water systems. It is a special advantage of the preferred embodiment of the invention that an extraordinary rapid flow of water and uniform distribution is obtained by the special design of heat absorbing elements which will be illustrated.

It is a further advantage that in the preferred 60 designs, water flows into the auxiliary heat absorbing elements through pipes which can be connected to the hot water or steam pipes at the top of the heater and the cold water return or condensate pipes at the bottom of the heater through ordinary pipe fittings requiring no special equipment and permitting rapid assembly with a correspondingly low installation cost.

Another feature of the preferred design of auxiliary heating surfaces is that they have relatively thin walls which may be made from welded sheet metal since the auxiliary heating surface is flexibly supported in the furnace and is not subject to differential warping or other stresses 75 which require the relatively heavy walls of the

furnace proper. The thin sheet steel construction is not only highly economical, but also permits an extremely rapid heat transfer which is particularly effective since the lower portions of the auxiliary surface are situated where they absorb most of the radiant heat of the flame. In fact in many installations the auxiliary heating surface, although small in area compared with the total heating surface of the boiler, may actually absorb almost as much or actually more heat than the rest of the boiler. 80 85

Another advantage of this particular modification of the invention as especially adapted to a common type of sectional boiler lies in the fact that by a peculiar shape of the upper surfaces, the gases are deflected into contact with the side walls to a very marked degree, thus not only adding heat absorbing surface of the auxiliary members but greatly increasing the heat absorbing efficiency of the water jacketed side walls of the furnace which in ordinary installations operate with very low effectiveness by reason of the fact that hot combustion gases are not forced intimately in contact with these surfaces. 90 95

In the drawings the invention will be shown 100 as applied to two common types of domestic heaters, a sectional boiler and a typical round boiler. The invention is however in no sense limited to these particular designs of boiler but on the contrary is generally applicable to all coal fired boilers 105 with suitable changes in the shape of the two auxiliary heating members to conform to the shape of the fire box.

In the drawings the auxiliary heating surface is shown as fitting tightly against the side walls 110 of the fire box. It should be understood, however, that the essential principles of the present invention are equally applicable to auxiliary heating members which fit loosely against the walls of a fire box, as complete gas tightness is 115 not essential, for if a small amount of gas passes up between the edges of the auxiliary heating members and the fire box walls it is forced intimately into contact with these walls and the efficient utilization of the surfaces is therefore 120 preserved. In fact in some designs a small leakage around the edges of the auxiliary member is actually desirable and produces a more satisfactory flow of heating gases. Where a tight fit is 125 desired, particularly where in the case of common sectional boilers, the inner surfaces are slightly arched, the auxiliary members may be provided with non-uniform edges to conform with the shape of the sections, or the interstices between the straight edge of the auxiliary member and the low points where sections join each other may either be filled in with cement or closed by means of a metal fin which can be welded on to the auxiliary heating member. In the drawings 135 the interstices are shown as filled with cement, a method which is effective in the particular design of sectional boiler as shown, but it should be understood that the invention is not limited to this method of tightening, even with the particular design of boiler shown in the drawings. 130 140

In the drawings, Fig. 1 is a side elevation partly broken away, of a sectional boiler.

Fig. 2 is horizontal section through Fig. 1 along the line 2-2; 145

Fig. 3 is a front elevation, partly broken away, of the boiler of Fig. 1;

Fig. 4 is a horizontal section of auxiliary member, partly broken, along the line 4-4 of Fig. 3 looking up from the bottom; and 150

Fig. 5 is a horizontal section through a typical round boiler.

In the modification shown in Figs. 1-4, the boiler consists of a front section 1, two center sections 2, and a rear section 3; the front section and two center sections being provided with two water legs, 4 and 5, while the front section is provided with a single water leg, 6, at the level of the legs 5 of the center sections and the rear section is provided with a water leg 7, at the level of sections 4. This design forms two passes above the fire box as shown in Fig. 1, the gases flowing up at the rear, forward through the first pass, the two flues, and then back, through the second pass, leaving through the stack 8. An oil burner is shown diagrammatically at 9, directing its flame into the ash pit 10 which is preferably lined with fire brick. An oil burner of the gun type is shown but it is obvious that any other standard type of oil burner may be used or an underfeed coal stoker may be installed. From the fire brick lining which extends up to the bottom of the sections 1, 2, and 3 which normally surround the fire box, relatively narrow columns of fire brick are built up to a level slightly above the lower edge of the fire door. Two of these columns shown at 11 (Figs. 2 and 3) are at the rear corners of the fire box, a somewhat wider column 12 extends up the center of the rear section, while two other columns 13 are located at the rear of the first section. On these columns rest two hollow heating members 14. These heating members, which in the drawings are shown as constructed of sheet steel, are provided with a relatively flat lower surface 15 which is immediately above the flame of the oil burner and their upper surfaces 16 are arched, being curved over the out flow pipes 17. The central edges 18 of the heating members are parallel, and preferably set together to provide a gas tight or substantially gas tight joint. The straight outer edges 19 of the members abut against the points 20 of the arched inner surfaces of the boiler sections. The triangular spaces 21 between the straight walls of the auxiliary heating elements and the thinner portions of the boiler sections are filled in with furnace cement (see Fig. 2).

The auxiliary members are also provided with water inlet tubes 22 which preferably extend substantially to the rear of the members and are provided with perforations at their sides (see Figs. 3 and 4) so that water flowing in through these pipes is directed laterally along the bottom surface of the auxiliary elements. The out flow pipes 17 are similarly provided with slots in their lower portions and are connected by means of suitable unions 23 to a header 24 from which a pipe extends upwardly to the hot water or steam riser pipes at the top of the boiler. Similarly cold water from the cold water or condensate return pipes of the boiler flows into a header 25 which is connected through unions 26 to the water inlet pipes 22. The particular design of water pipes in the heating elements assures a very rapid and very uniform circulation of water which is essential to satisfactory operation because of the rapidity with which the auxiliary elements absorb heat. This rapid circulation also prevents local overheating which might result in warping of the elements.

The first pass formed by the water legs 5 and 6 with the arched upper surface of the element defines two channels of substantially triangular cross section. This provides considerable in-

creases in surface exposed to the gases and also results in forcing a considerable portion of the gases into contact with the side walls of the sections, thus increasing the effectiveness with which these portions of the boiler absorb heat. 80 While this design of auxiliary elements combined with the particular shape of the sections of the boilers shown in the drawings result in a very efficient heat absorption, it should be understood that the invention is not limited to this particular shape of auxiliary heating elements and on the contrary many shapes of auxiliary heating elements may be used which will form a practically gas tight joint and substantially cover the fire box area from side to side, although in its preferred embodiment the present invention contemplates the use of shapes which will result in a comparatively narrow pass between the upper surface of the auxiliary elements and the lower legs of the sections so as to provide for maximum 90 turbulence. 95

In its broader aspects the invention is not limited to the particular design of water inlet and outlet tubes illustrated in the drawings but in its preferred embodiment the accelerated flow 100 obtained by the distribution of the water through the openings in the tubes constitutes an additional advantage of the specific embodiment of the invention.

It will be noted that the auxiliary heating members rest on five columns of fire brick, each member, therefore, being supported at three corners only, although additional support of a flexible nature is afforded by the tubes 17 and 22. Since 105 the auxiliary heating elements are supported only at three corners, they are free to move slightly if differential heating results in any slight temporary or permanent warping and there is, therefore, no danger of breaking the members 110 due to strains set up by warping which might be a serious problem if they were rigidly supported. This flexible support of the auxiliary members is an important advantage of the preferred embodiment of the invention, but in its 115 broader aspects, the invention is not limited to this type of support and suitable rigid supports may be employed where desired. In some cases the fire brick columns may be replaced by thin metal legs, thereby preventing the screening of 120 small portions of the heating surfaces by the fire brick. Since however, the heating surfaces in this lower portion of the boiler operate at a relatively low efficiency, the loss by the insulating effect is slight and the fire brick construction has the advantage that it is not subject to warping and 125 softening if the heat is excessive, which might be a factor if relatively thin metal supporting legs were employed.

Fig. 5 illustrates the application of the present 130 invention to a circular boiler. The shape of the auxiliary surfaces is, of course, somewhat different in order to accommodate themselves to the shape of the round fire box. The round water cooled fire box wall is shown at 27 and the parts 135 of the auxiliary heating elements corresponding to those in Figs. 1 to 4, bear the same members. Because of the relatively short pass horizontally 140 which is a characteristic of a round boiler, it is desirable to increase the effectiveness of the side wall and this may be brought about by slightly 145 spacing the outer edges of the auxiliary heating elements from the side wall to permit a portion of the gases to flow up the side wall being closely confined thereto by the narrow divide between the auxiliary heating members and the fire box wall. 150

This construction is not shown in Fig. 5 for the sake of simplicity, but its application is, of course, obvious.

While the present invention is particularly important as an auxiliary heating device for application to coal burning domestic heaters which have not been designed for the installation of oil burning equipment, it should be understood that the invention may be applied to specially designed equipment, thus for example, coal burning domestic heaters may be built with shelves or projections on which the auxiliary heating members may best rest, thus obviating the necessity for fire brick columns or metal legs. Designs may also be provided in which the auxiliary members may be hung from rods from the first pass and it should be understood that such suitable modifications of the invention are included, although it is a particular advantage of the preferred embodiment of the invention that it may be applied to equipment which was never designed for oil burning and without necessitating any structural changes. The design of auxiliary heating surface of the present invention particularly in the preferred embodiment illustrated is distinguished by a great manufacturing economy, for the units are cheap to make and they are so simple and so easily connected to heaters that the cost of installation is unusually low.

The present invention has been described and illustrated particularly in connection with oil burning equipment because the great demand for the installation of such equipment in coal burning domestic heaters renders this field of primary commercial importance. A similar problem, though not quite as acute is presented by various underfeed coal stokers which are installed in many domestic heaters and which employ an air blast resulting in a combustion which has many of the features of an oil burner. The problem is not of as great economic importance with underfeed coal stokers as with oil burners because the combustion gas speeds are somewhat lower and because the lower cost of the heat units in the very cheap fine sizes of coal employed in such stokers renders their efficiency of less immediate economic importance. However, although, the waste due to insufficient heat absorption with underfeed coal stokers is not as great as with oil burners, it is nevertheless an important item and, of course, the present invention solves the problems presented by an underfeed coal stoker as applied to a domestic furnace designed for hand firing in precisely the same way as with an oil burner and it should be understood that the present invention is equally applicable to installations in which underfeed coal stokers are used.

What I claim is:

1. In combination a domestic heater of the hot water or steam type having heating surfaces designed for hand fired coal operation and a detachable auxiliary heating surface consisting of a plurality of abutting sections disposed in the fire box area and extending substantially across the maximum width thereof and spaced sufficiently from at least one side of the fire box so as to permit upward passage of the gases through the opening thus formed and constituting an additional pass, each section having its greatest dimensions in a horizontal plane and being of sufficiently smaller width than the fire door to permit introduction therethrough and means connecting each section to the water system of the heater at a point below the lowest point of the section and at a point above the highest point of

the section, and a fuel burner of the blower actuated type in the ash pit of said heater.

2. A domestic heater according to claim 1 in which the abutting auxiliary heating members are sufficiently spaced from one of the two ends of the fire box so as to constitute a baffle defining with the lowest horizontal heating surface of the heater an additional pass from the combustion gases. 80

3. A domestic heater according to claim 1 in which the connections from the auxiliary heating members are to pipes in the heating system outside of the heater itself. 85

4. A sectional domestic heater of the hot water or steam type designed for hand fired coal operation and having a fire box of rectangular section and horizontal fore and aft heating flue passages defined by the sections, in combination with a plurality of abutting horizontally disposed auxiliary heating surfaces of widths sufficiently less than the opening of the fire door to permit insertion therethrough, but when abutting extending substantially across the fire box area horizontally and fitting substantially gas tightly against one end of the fire box and being spaced from the other end, the spaced portion being at the end opposite to the opening into the lowest flue pass whereby a complete additional pass for the combustion gases is defined and a fuel burner of the blower actuated type disclosed in the ash pit of the heater, each auxiliary heating member being provided with connections to the upper and lower portions of the water or steam circuit in the heater respectively. 90

5. A domestic heater according to claim 1 in which the auxiliary heating members rest on supports at not more than three points whereby warping of the individual members by reason of non-uniform heating will not result in strains in the members. 100

6. A domestic heater according to claim 1 in which the auxiliary heating elements are provided with water inlet and outlet tubes extending horizontally therethrough from front to back and provided with discharge openings along their lengths whereby uniform water circulation is effected. 115

7. A domestic heater according to claim 4 in which the auxiliary heating elements are provided with water inlet and outlet tubes extending horizontally therethrough from front to back and provided with discharge openings along their lengths whereby uniform water circulation is effected. 125

8. A domestic heater according to claim 1 in which the auxiliary heating elements are provided with water inlet and outlet tubes extending horizontally therethrough from front to back and provided with discharge openings along their lengths whereby uniform water circulation is effected, the water inlet tube being below the water outlet tube and provided with lateral discharge openings and the water outlet tube being provided with openings along its lower surface. 130

9. A domestic heater according to claim 4 in which the auxiliary heating elements are provided with water inlet and outlet tubes extending horizontally therethrough from front to back and provided with discharge openings along their lengths whereby uniform water circulation is effected, the water inlet tube being below the water outlet tube and provided with lateral discharge openings and the water outlet tube being provided with openings along its lower surface. 140

10. A domestic heater according to claim 4 in 150

which the auxiliary members are of pentagonal cross section, the lower surface being substantially flat, the side surfaces being likewise substantially flat and at right angles to the bottom surface and 5 the two upper surfaces forming an angle which defines with the bottom of the heating surfaces forming the lowest flue passes flues of substantially triangular cross section.

11. A domestic heater according to claim 4 in
10

which the surfaces of the sections surrounding the fire box are of slightly arched cross section and the outer edges of the auxiliary members are substantially straight, the flat triangular spaces between the apices of the arches being filled with cement to form with the outer edges of the auxiliary heating members a substantial gas tight joint. 80
